Fig. 1

Fig. 2

Fig. 3

FIG. 1 is a perspective view of an envelope opening machine showing my design;

FIG. 2 is a side elevation view of the machine of FIG. 1 with identical portions omitted for drafting convenience; and

FIG. 3 is a plan view of the envelope opening machine of FIG. 1 with identical portions omitted for drafting convenience.

The back side and opposite side of the housing of the envelope opening machine is identical to the side shown in FIG. 2 and, therefore, is not illustrated in the drawings.

What is claimed is:

The ornamental design for an envelope opening machine, substantially as shown and described.
